UNITED STATES PATENT OFFICE

CARL D. HANNA, OF BROOKLYN, NEW YORK

BOAT

Application filed February 4, 1930. Serial No. 425,833.

This invention relates to boats and more particularly to boats of the sea going type and has for one of its objects to provide, in a manner as hereinafter set forth, a boat of this character embodying an improved construction and arrangement of propulsion mechanism.

Another important object of the invention is to provide a boat of the aforementioned character embodying propelling means of a construction and arrangement which will drive the boat through the water at a greatly increased speed with a given expenditure of power as compared with boats now in use.

Other objects of the invention are to provide a boat which will be very sea worthy, strong, durable, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of a boat constructed in accordance with this invention.

Figure 2 is a view in side elevation thereof.

Figure 3 is a vertical cross sectional view therethrough.

Figure 4 is a detail view in side elevation showing one of the closure disks of the depending propeller guard plate raised in a manner to expose the adjacent propeller.

Figure 5 is a fragmentary detail view on an enlarged scale in side elevation and partly in longitudinal section of one of the propellers.

Figure 6 is a vertical cross sectional view taken substantially on the line 6-6 of Figure 5 and looking in the direction of the arrows.

Figure 7 is a sectional view taken substantially on the line 7-7 of Figure 5 looking in the direction of the arrows.

Referring to the drawings in detail, the reference character 1 designates generally the hull of the boat having the rounded stern portion 2 and the comparatively pointed prow portion 3.

On opposite sides, and extending from the prow to the stern portion thereof, the hull 1 is shaped to provide longitudinally extending compartments 4-4 which extend a substantial distance above the water line of the vessel, as illustrated to advantage in Figures 2 and 3 of the drawings. The compartments 4-4 are open at their opposite ends for the entrance and exit of the water when the boat is in motion. Guard plates 5-5 constitute the outer walls of the compartments 4-4, as best seen in Figure 3 of the drawings and which form a continuation of the side walls of the hull. The lower inner walls 21 of the compartments below the water line extend or slope downwardly and outwardly and meet the plates 5-5 adjacent the bottom of the hull.

At longitudinally spaced points, the hull 1 has mounted for rotation therein the horizontally disposed transversely extending propeller shafts 6 which have their opposite ends projecting into the compartments 4-4 at a point slightly above the water line of the boat and terminating substantially in the plane of the guard plates or walls 5-5. Fixed on each end of the propeller shafts 6 is a propeller wheel designated generally by the reference numeral 7 and illustrated in detail in Figures 5, 6 and 7 of the drawings. Co-axially with the outer ends of the propeller shafts 6 the guard plates 5-5 are provided with circular openings 8 of a diameter larger than the diameter of the propeller wheels 7 to permit access to be had to the propellers 7 and for their attachment and removal from the shaft 8 and said openings 8 are closed through the medium of the flat closure disks or plates 9 (see Figures 3 and 4) hingedly connected to the sides of the hull 1 as at 10 and provided with suitable means such as an eye bolt 11 to permit a hoisting cable 12 to be coupled thereto for the purpose of raising the closure disks to open position when it is so desired. The eye bolt 11 is turnably mounted in the door and carried by the inner end thereof is a catch member 22 which may be turned to engage or disengage the inner side of the outer plate 5. The propeller shafts 6 may be operatively connected in any

suitable manner to any suitable type of power plant for actuation thereby.

Each of the propellers 7 comprises a hub portion 13 from the opposite end portion of which extends the outwardly converging conical side wall 14, as best seen in Figure 6. It will be seen that each of the propeller shafts 6 is provided with an annular stop flange 15 disposed within the respective compartments 4-4 for engagement by the inner end of the hub 13 and a flanged nut 16 is threaded into the outer end of the propeller shafts for securing the propellers thereon, but it is to be understood that the propellers may be fixed to the shafts 6 in any suitable manner. Paddles or vanes 17 are mounted on the conical side walls 14 of the propellers 7 and radiate from the opposite end portion of the hub 13 and said vanes are substantially triangular in shape. The outer marginal edges 18 of the vanes 17 are straight and disposed at right angles to the hub 13 while the inner edges thereof conform to the conical side walls 14, as best seen in Figure 6. The outer or free ends of the vanes 17 are rounded and extend slightly beyond the periphery of the converged ends of the side walls 14. It will also be seen that the driving or water engaging face of each of the vanes 17 is concaved, as indicated at 19 for the purpose of trapping the water therein and causing the propeller to function at maximum efficiency. The outer front sides of the vanes 17 are provided with grooves or notches 20 to permit any water picked up by the vanes to quickly drain therefrom as each vane rises from the water.

It is believed that the many advantages of a boat constructed in accordance with this invention will be readily understood, and although the preferred embodiment of the invention is as illustrated and described, it is to be understood that the changes in the details of construction may be had which will fall within the scope of the invention as claimed.

What is claimed is:—

A boat of the class described comprising a hull having a longitudinally extending compartment in each side thereof, the upper part of which is above the water line and the lower wall of which slopes downwardly and outwardly, a plate forming a continuation of a side of the hull and covering the compartment, but leaving the ends thereof open whereby water can pass thru the compartment, a number of power wheels in each compartment, means for rotating the wheels, each plate having an opening therein of circular shape and of larger diameter than a wheel for entirely exposing the wheel, a cover plate hingedly connected to the plate at the top of the opening for covering said opening, and catch means for holding the cover plate in closed position.

In testimony whereof I affix my signature.
CARL D. HANNA.
